JACK

Forrest L. Shire, St. Joseph, Mich., assignor to
Auto Specialties Manufacturing Company,
San Francisco, Calif., a corporation of California

Application October 24, 1930. Serial No. 490,957

1 Claim. (Cl. 254—102)

My invention relates in general to lifting jacks and has more particular reference to lifting jacks for vehicles characterized by the capacity for collapsing to small minimum height, where-
5 by the jack may be positioned under a low object to be lifted and then extended to a maximum height, substantially in excess of two times the minimum collapsed height, whereby the jack can be successfully used on modern balloon tire
10 automobiles.

Among the important objects of my present invention is to provide a jack of the double lift type having a novel and simple construction whereby the jack can be made commercially
15 at low cost, wherein the operating parts are at all times protected from external dirt and moisture, and from injury, wherein the operating parts comprise extensible telescoping screw members arranged in a novel manner and adapt-
20 ed for projection and retraction solely by the operation of the driving member without the intervention of external forces and wherein the extensible members are operated solely by externally driven means located in the base of the
25 jack assembly to keep low the center of gravity of the assembly and thus to provide an easily positionable, substantially non-tipping vehicle jack.

These and numerous other objects of my in-
30 vention will be apparent from the following description, which taken with the accompanying drawing discloses a preferred embodiment of the invention.

Referring to the drawing:
35 Figure 1 is a vertical cross section taken through a jack embodying my invention, the jack being shown in fully collapsed position;

Figure 2 is a vertical cross section taken through the jack of Figure 1, the jack being
40 shown in partially extended position and the section being taken at right angles to that of Figure 1;

Figure 3 is a horizontal cross section taken substantially along the line 3—3 of Figure 2;
45 and

Figure 4 is a vertical cross section similar to Figure 2, the jack being shown in fully extended position.

To illustrate my invention, I have shown on
50 the drawing, a jack comprising a tubular housing 11 of preferably cylindrical construction upstanding from a base 13 which forms a broad support for the jack.

The upper end of the housing 11 is or may be
55 provided with an inwardly extending annular portion 15 defining a central opening having inwardly extending projections 17 on opposite sides of the opening 15.

The lower end of the housing 11 opens in an
60 enlarged portion 19 providing a recess in which a

horizontally extending driving gear 21 is or may be mounted for rotation about a vertical axis concentric with the bore of the housing 11. The housing also is or may be braced by webs 23 of conventional form. The gear 21 also is or may be journaled on the bottom of the housing by any suitable anti-friction means 25, specifically shown in the drawing as a ball bearing device mounted in a seat 27 formed in the base of the housing.

The gear 21 is preferably of the bevelled type and is driven from outside of the base by means of a co-operating bevelled pinion 29 formed on a stub shaft 31 which is journaled in a bearing 33 formed in the walls of the base in position such that the outer end 35 of the shaft extends at a convenient angle to receive the end of a driving crank or other means whereby the driving mechanism may be rotated. The stub shaft has an axially extending opening 37 adapted to receive the end of a driving member. The pinion is housed in a recess 39 formed in one side of the base at the lower end of the tubular portion 11.

The gear 21 carries an upstanding internally threaded sleeve 41, preferably formed integrally with the gear and having smooth outer wall surfaces adapted to engage and be supported by the walls of the tubular portion 11 of the base. The sleeve 41 extends upwardly in the standard 90 11, terminating just under the annular flange 15.

The internally threaded sleeve 41 is adapted to receive an externally threaded nut 43, which nut carries a co-axial upwardly extending shaft 95 45, which is also externally threaded.

Telescoping upon the shaft 45 and into the sleeve 41 are a pair of telescoping sleeves, the inner sleeve 47 being splined to the outer sleeve 49, which in turn is splined to the upper end 100 of the base. The sleeves 47 and 49 are preferably made of sheet metal and are configurated to provide cylinders having longitudinal inwardly displaced portions 51 on opposite sides of the cylindrical sleeves. The inwardly displaced portions provide longitudinal grooves in the outer walls of the sleeves and corresponding internal beads on the inner walls and the configuration is such that the outer grooves of the inner sleeve 47 are shaped to slidably receive the inner beads of the outer sleeve, and the outer grooves of the outer sleeve 49 are sufficiently wide to receive the projections 17 at the upper end of the base 11. In this way the 115 sleeves are slidably splined together and the outer sleeve is splined to the base. The external diameter of the outer sleeve 49 also is such that the sleeve makes a close sliding fit through the opening at the upper end of the base so 120

that the annular flange provides lateral support for the sleeves.

The inner sleeve 47 is provided at its upper end with a load carrying head 53 and at its lower end with an internally threaded nut 55, which is embraced within and secured to the lower end of the sleeve 47. The nut 55 is adapted to thread upon the rod 45.

Operation

If it is desired to extend the lifting member 47 from collapsed position shown in Figure 1 of the drawing, the driving pinion 29 is rotated conventionally in a clockwise direction. The gear 21 is consequently rotated in a clockwise direction viewed from above. The inner sleeve 47, being held from rotation by splined engagement with the upper end of the base through the nesting splines 51 of the sleeves 20 and the projection 17 of the base, will be projected because of its double threaded connection with the driving means, which double connection comprises the threaded connection of the nut 55 on the threaded shank 45, and the 25 threaded connection between the nut 43 formed to the lower end of the shank 45, which latter nut threads into the internal threads of the sleeve 41. When the sleeve 41 is initially rotated, the frictional resistance between the 30 threads of the nut 43 and of the sleeve 41 will be greater than the frictional resistance between the nut 55 and the shank 45. Consequently, the shank 45 will turn in the nut 55 and cause the lifting member 47 to be projected. 25 This projection will continue until the upper edge of the nut 55 locks upon a stop 57 formed in the upper end of the shank 45. When the stop 57 engages the upper side of the nut 55, the shank 45 will be prevented from rotating. 40 The nut 43 at the lower end of the shank 45 also will be held from rotation so that continued rotation of the driving sleeve 41 will elevate the nut 43 therein and this in turn will raise the shank 45 and the lifting member 47 45 until the fully extended position illustrated in Figure 4 of the drawing is reached.

Reversal of the driving rotation of course will reverse the operation of the elevating screws and will retract the lifting member until fully collapsed position is again reached. It should be noted that the nut 43 and the shank 45 are threaded in the same direction and inasmuch as conformation requires that jacks be extended in response to a clock-wise motion of the driving handle outside of the jack, the nut 43 and shank 45 are illustrated as having right hand threads, in order to project the lifting member 47 upwardly when the pinion 29 is rotated in a clock-wise direction in accordance with prevailing custom.

It will be noted that when the jack is in fully extended position as in Figure 4 of the drawing, all of the threaded operating parts are entirely enclosed by imperforate sleeve members 65 including the sleeve '47 forming the upper lifting member and the intermediate sleeve '49 which sleeve also is splined to the base to prevent the upper member from rotating whereby the threaded members are enabled to automatically project the upper lifting member to a height substantially in excess of twice the collapsed height of the jack. The construction obviously 70 will exclude foreign matter from entering the

jack and deteriorating its operating parts. The sleeve-like members also protect the threaded members when the jack is extended or partially extended so that if thrown into a tool box and rattled about with other contents of the tool box, the threaded operating screws will not be damaged. 80

I desire also to call attention to the fact that the upper lifting member comprising the sleeve 47 and lifting head, the intermediate sleeve 49, the internally threaded nut 55 in the bottom of the sleeve 47 and the member comprising the threaded portions 43 and 45 are identical to the similar portions shown in my co-pending application, Serial No. 487,736 filed Oct. 10, 1930 covering a jack in which the driving impulse is delivered at the upper end of the jack standard. 85 90

In the embodiment illustrated in my co-pending application, the part corresponding to the threaded portion 43 is threaded directly into the cylindrical portion of the jack base, which is provided with suitable screw threads and the part corresponding to the sleeve 49 of the present application is splined through a rotatable driving nut or collar, which is mounted to the upper end of the jack casing approximately in the relative position occupied by the splines 17 in the present application, so that by rotating the collar, the upper or load-carrying projectable member is rotated with respect to the base, which results in the successive projection of the load-carrying and lifting members through the action of the threaded connection therebetween and the stop means corresponding to the element 57 of the present application. I have thus designed two radically different types of jack, the major portions of which are interchangeable, it being merely necessary to assemble with the lifting mechanism a base and driving mechanism of desired type in order to obtain the two types of jack. In this way I am able to greatly reduce the cost of producing jacks of both types by thus reducing the number of necessary parts for both jacks.

It is thought that the invention and numerous attendant advantages will be more fully understood from the foregoing description and it is obvious that numerous changes may be made in the form, construction and arrangement of the several parts without departing from the spirit or scope of my invention or sacrificing any of its attendant advantages. 120 125

Having thus described my invention what I claim as new and desire to secure by Letters Patent is:

In a lifting jack having a support frame, the combination of a driving member mounted in the frame, driving means formed at one end of the driving member and extending outwardly thereof, a lifting member having telescopic relation and threaded connection with the driving member and a second lifting member having telescopic relationship and threaded engagement with said first lifting member, said driving member and said lifting members being arranged so that when in collapsed position the second lifting member encloses a part at least of the first lifting member and both nest within the driving member when the jack is in collapsed position and means for preventing rotation of the second lifting member during its longitudinal movement.

FORREST L. SHIRE
